UNITED STATES PATENT OFFICE.

WILFRED SHURTLEFF, OF MOLINE, ILLINOIS.

FUEL FEEDING AND MIXING DEVICE FOR GAS-ENGINES.

1,338,104.

Specification of Letters Patent. Patented Apr. 27, 1920.

Application filed March 16, 1917. Serial No. 155,305.

To all whom it may concern:

Be it known that I, WILFRED SHURTLEFF, a citizen of the United States, and a resident of Moline, in the county of Rock Island and State of Illinois, have invented 5 certain new and useful Improvements in Fuel-Feeding and Mixing Devices for Gas-Engines, of which the following is a specification.

10 My invention relates to fuel feeding and mixing devices for gas engines, particularly to that class in which a fuel mixer or carbureter is connected with a float chamber to receive fluid therefrom and in which the 15 suction caused by the flow of the fuel mixture through the mixing chamber serves to draw fresh supplies of fluid to the float chamber from a supply tank situated below such chamber, the float operating to control 20 the flow of oil into the float chamber.

Heretofore, in devices of this class, the float was utilized to actuate oil valves which directly control the flow of oil to the float chamber.

25 One of the important objects of my invention is to eliminate such oil flow valves and to control the level of the oil in the float chamber by having the float automatically control the inflow of air to the mixing chamber by actuating suitable throttle valves.

30 Another object of my invention is to provide such construction, arrangement and operation as will automatically reduce the suction or drawing effect of the carbureter 35 on the float chamber to the smallest amount necessary to lift the fluid from the supply tank thereby increasing the maximum power of the engine and making the device particularly efficient on low lifts. Another

40 object of the invention is to utilize the exhaust pressure from the engine cylinders by projecting a hot blast of exhaust gases through the carbureter mixing chamber and to cause such blast to entrain with it proper 45 quantities of fluid from the float chamber.

The above and other features of my invention are embodied in the devices shown on the accompanying drawings in which—

50 Figure 1 is a vertical diametral section of a fuel feeding and mixing device;

Fig. 2 is a sectional view on plane 2—2,

Fig. 1,

55 Fig. 3 is a more or less diagrammatical view showing an improved construction and arrangement for a feeding and mixing de-

vice and connection thereof with the engine, and

Fig. 4 is a vertical diametral sectional view of the feeding and mixing device shown in Fig. 3. 60

Referring to Figs. 1 and 2, a cylindrical cup-shaped casting 10 forms a receptacle for fuel and a chamber for the float 11. At one side near the top of the receptacle is the threaded lug 12 for receiving the fitting 13 to which is connected the pipe 14 leading from a fluid supply tank situated below the receptacle 10. Closing the top of the cylindrical container 10 is the cover 15 which has the housing 16 extending diametrically thereon to form the air intake passageway 17 to the carbureter or mixing chamber frame 18 extending vertically at one side of the container 10. This frame and the housing 16 70 and the cover 15 may be part of an integral casting. The frame 18 forms the generally cylindrical mixing chamber 19 in whose upper end is pivoted a butterfly valve 20 of ordinary design. In the mixing chamber 80 below the valve a Venturi tube 21 is secured by a screw 22, the adjacent walls of the housing 16 and frame 18 being contracted to form a throat 23 connecting with the passageway 24 leading to the lower end of 85 the Venturi tube. Extending laterally from the container 10 below the carbureter frame is the tube 25 from which the nozzle 26 extends upwardly through the base of the frame 18 and into the lower end of the Venturi tube, the fluid flowing from the float chamber into the tube 25 and the nozzle to be drawn into the carbureter mixing chamber and mixed with air preparatory to passage of the mixture to the engine. 95

In order to obtain the most efficient results, the fuel should be maintained as accurately as possible at a constant level in the float chamber and in the nozzle, and as soon as fluid is withdrawn from the float chamber additional fluid should be drawn into the chamber from the supply tank through pipe 14. Passage of the mixture from the carbureter mixing chamber to the engine causes suction effect which draws fluid from the nozzle and which also draws air into the mixing chamber through the air intake passageway 17, and I utilize part of the suction effect to draw in fresh fluid supplies into the float chamber. In the cover 100

105

110

15 of the float chamber I provide an opening 27 through which the suction effect can be transmitted to the float chamber, that is, the suction which tends to draw air into the 5 mixing chamber through the intake passageway 17 tends also to draw air out of the float chamber, this resulting in flow of oil into the float chamber. One of the important features of my invention is the control 10 of such fluid inflow by the control of air flow through intake 17 by the float. Interposed in the air intake is the loop 28 whose upper and lower walls 29 and 30 have the ports 31 and 32 respectively. The 15 stem 33 supported by the float 11 extends through the suction hole 29 and through the ports 32 and 31 and carries the valve disks 34 and 35 above the walls 29 and 30 for controlling respectively the ports 31 and 20 32 as the float rises and falls. At its upper end the float is guided by its end 36 which extends through the guide hole 37 in the housing 16, and at its lower end the stem is guided in the cup 38 screwed into the base 25 of the float container 10. The arrangement is such that when the fluid rises in the float chamber the float will rise and the valves will open the air ports, and when the fluid level drops the float will fall and will 30 carry the valves toward closing position. On the drawing the valves are shown in normal position, the fluid being at the level which should give the most efficient results. As soon as the fluid level drops the valves 35 will decrease the passageway through the ports and a greater percentage of the suction force in the mixing chamber is effective in the float chamber by way of the hole 27 and fluid is immediately drawn into the 40 float chamber from the supply tank. The inflowing fluid raises the level and causes the float to rise and the valves to open further the port passageways, and the suction effect in the float chamber is gradually diminished 45 until the normal level is again attained. Should there be an excess flow of fuel into the float chamber, the valves will be raised to permit a greater quantity of air to flow through the air ports 31 and 32 and 50 the suction effect in the float chamber will be correspondingly reduced or will be destroyed so that there will be no influx of fuel until the normal level is restored. If the level is so low that the valves are entirely 55 closed, then the suction effect in the mixing chamber is all effective in the float chamber and fresh supply of fluid is quickly drawn into the float chamber to restore the level. If the float chamber is entirely 60 empty, then suction effect is communicated to the float chamber through the nozzle 26 and tube 25 as well as through the hole 27 and the fluid level is quickly brought to normal. Thus the float shifts with the 65 varying oil level and by its valves controls

and adjusts the air inflow to the carburetor and such flow adjustment automatically controls the degree of suction in the float chamber which draws fluid into the float chamber, the operation and co-operation being 70 such as will tend to maintain the normal level which will insure the most efficient operation of the device in supplying combustible mixture to the engine. It will be noted that in my improved arrangement 75 there are no fluid valves of any kind, but that the fluid is free at all times to flow from the main reservoir to the float chamber and from the float chamber to the carburetor mixing chamber. Different valve 80 construction and arrangement could be used for controlling the air intake with the carburetor, but by using the two valve disks as shown the entire valve structure is balanced. With my improved construction and 85 arrangement the amount of suction necessary to lift fluid into the float chamber is reduced to a minimum, and this increases the maximum power of the engine which is supplied by the device, and the operation 90 of the device is particularly efficient on low lifts.

In Figs. 3 and 4 I have shown a modified construction and arrangement in which the exhaust pressure from the engine is utilized 95 in the form of a hot blast projected into the carburetor mixing chamber. In other respects the operation is the same as in the structure of Figs. 1 and 2. Referring to Fig. 4, the float chamber 40 is connected by 100 pipe 41 with the supply tank, the fluid passing from the float chamber through the tubular extension 42 into a well formed at the bottom of the mixing chamber frame 43 whose outlet is controlled by the valve 44 105 provided with the throttle lever 45 controllable from a distance. Projecting into the bottom of the frame 43 in line with the tube 42 is a blast nozzle 46 which is connected by a pipe 47 with the exhaust manifold *a* of an 110 engine represented by *e*. As only a part of the exhaust pressure is necessary for sufficient blast effect, the end of the pipe may project into the exhaust manifold with its end 48 flared to an inlet area which will 115 draw from the exhaust manifold a sufficient amount of flow to get the necessary blast pressure at the nozzle 46. The fuel at the bottom of frame 43 is controlled to surround the end of the nozzle 46 and to overflow the 120 outlet so that the hot blast will pick up fluid and atomize it and discharge it into the mixing chamber in the form of a spray. The flow of the fluid from the float chamber is preferably controlled by a restricted orifice 125 49 provided in the plug or bushing 50 inserted in the tube 42, this orifice preventing sudden rushes of the fluid and causing it to flow more gradually.

Above the float chamber is the air intake 51 13

through which air is drawn into the mixing chamber in frame 43 to mix with the atomized fluid, and in the top of the float chamber is the hole 52 through which the suction effect can be transmitted to the float chamber to draw in new supplies of fluid as the level in the float chamber falls. A butterfly valve 53 is shown in the air intake and the upper end of the stem 54 of the float 55 is pivoted to the valve in such manner that when the float rises and falls the valve will be moved toward open or closed position in the air intake. The principle of control is the same as in the arrangements of Figs. 1 and 2. When the fluid level in the float chamber drops the valve 53 will be moved toward closed position so that less air can flow through the intake, and a greater percentage of the suction effect can become effective in the float chamber to draw in a fresh supply of fluid. When the level rises the valve is opened farther and the suction effect in the float chamber is reduced, the float controlled by the fluid level thus controlling the air flow through the intake and the degree of suction effect in the float chamber and the replenishment of fluid so that the tendency is to automatically maintain the fluid level at a point where fluid will be most efficiently fed to the nozzle 46 to be acted on by the hot blast.

I thus provide a simple and very efficient fuel feeding and mixing device in which the fuel level in the float chamber and the proper proportioning of fluid and air in the mixing chamber are automatically controlled by the movement of simple air valve mechanism by the float.

I do not desire to be limited to the exact construction, arrangements and operations described as changes and modifications are no doubt possible which would still fall within the scope of the invention. I claim as follows:

45 1. In a device of the class described, the combination of a fuel reservoir having a fuel inlet at its upper end adapted for connection with a fuel supply tank below the reservoir, a mixing chamber, a fuel outlet from said reservoir to the lower end of said mixing chamber, an opening connecting said mixing chamber with said reservoir above the level of fuel therein, an air intake passageway to the mixing chamber, means for causing the flow of fuel and air into and through said mixing chamber whereby to create suction effect in said air intake passageway and reservoir, and means controlled by the level of fuel in said reservoir 55 for adjusting the area of said air intake passageway whereby to control of the suction effect in said reservoir and thereby to control the inflow of fuel and the level thereof in said reservoir.

60 2. In a device of the class described, the

combination of a fuel reservoir having an inlet at its upper end for connection with a fuel supply tank placed below the reservoir, a mixing chamber connected at its lower end with said reservoir for the flow of fuel, an opening connecting said mixing chamber with said reservoir above the level of fuel therein, the passageway for connecting said mixing chamber with the atmosphere for the inlet of air, means for causing the flow of fuel and air into and through said mixing chamber whereby to produce suction effect in said air passageway and in said reservoir, a float in said reservoir, and a throttle valve in said air intake passageway connected with said float to be shifted thereby in correspondence with the varying level of fuel in said reservoir to increase the opening or closure of said air intake passageway to thereby correspondingly decrease and increase the suction effect in said reservoir whereby the inflow of fuel and the level thereof in the reservoir is controlled.

3. In a device of the class described, the combination of a fuel reservoir having an inlet at its upper end adapted for connection with the fuel supply tank placed below the reservoir, a mixing chamber above the level of the fuel in the reservoir, an opening connecting the mixing chamber with the reservoir above the fuel therein, an atmosphere intake passageway to the mixing chamber, a throttle valve for said passageway, a float in said reservoir connected with said valve and actuated by the varying fuel level in said reservoir to operate said valve to increase or decrease the area of said air passageway with reference to said opening between the reservoir and mixing chamber whereby suction effect in said mixing chamber will be communicated in varying degree to said reservoir and the inflow of fuel and the level thereof in the reservoir controlled.

4. In a device of the class described, the combination of a fuel reservoir having a fuel inlet adapted for connection with a fuel supply source below the reservoir, a mixing chamber adapted by its connection with an engine to have suction effect created therein, a fuel inlet from the reservoir to said chamber, an opening between the upper part of said reservoir and said mixing chamber, whereby said reservoir is subjected to suction in said mixing chamber, an air intake passageway to the mixing chamber, and means controlled by the level of fuel in said reservoir for regulating the amount of air flow through said air intake passageway to thereby regulate the suction effected in said reservoir through said opening thereby controlling the inflow of fuel and the level thereof in said reservoir.

5. In a device of the class described, the combination of a fuel reservoir having a fuel inlet at its upper end adapted for con-

nection with a fuel source below the reservoir, a mixing chamber, a fuel inlet from said reservoir to said mixing chamber, an air inlet passageway to said mixing chamber, throttle valve mechanism for said air inlet passageway, and a float in said reservoir connected with said valve mechanism to operate said valve mechanism in accordance with the varying fuel level and to correspondingly control the air flow.

6. In a device of the class described, the combination of a fuel reservoir having a fuel inlet at its upper end adapted for connection with a fuel source below the reservoir, a mixing chamber having a fuel inlet thereto from said reservoir, an opening connecting the air space of said reservoir with said mixing chamber, a passageway for connecting atmosphere with said mixing chamber, means controlled by the level of fuel in said reservoir for automatically adjusting the air passageway relative to said opening whereby to control the degree of suction effect communicated from the mixing chamber to said reservoir thereby to control the inflow of fuel and the level thereof in said reservoir.

7. In combination with a gas engine, of a fuel feeding and mixing device comprising a fuel reservoir having a fuel inlet at its upper end adapted for connection with a fuel source below the reservoir, a mixing chamber connected at its upper end with the intake manifold of the engine whereby suction will be produced in the mixing chamber during operation of the engine, a fuel outlet from said reservoir to the bottom of said

mixing chamber, an opening connecting said mixing chamber with the upper part of said reservoir whereby suction effect may be communicated from the mixing chamber to the reservoir, an air intake passageway to said mixing chamber, a throttle valve in said air intake passageway, and a float in said reservoir connected with said throttle valve to be shifted by the varying fuel level to operate with the throttle valve to open or close the air intake passageway to thereby vary the degree of suction effect in said reservoir.

8. The combination with a gas engine, of a fuel feeding and mixing device comprising a fuel reservoir, a mixing chamber connected at its upper end with the intake manifold of the engine and provided at its lower end with a well communicating with said reservoir, a nozzle extending into said well, its outlet terminating below the fuel level therein, and a pipe connecting said nozzle with the exhaust manifold of the engine.

9. The combination with a gas engine, of a fuel carbureting device comprising a mixing chamber connected at its upper end with the intake manifold of the engine, and provided in the lower part thereof with a well, means for supplying fuel to said well, a nozzle extending into said well and having its outlet below the level of and overflowed by the fuel therein, said nozzle being connected with the exhaust manifold of the engine.

In witness whereof I hereunto subscribe my name this 10th day of March, A. D. 1917.

WILFRED SHURTLEFF.
